[57] **CLAIM**

The ornamental design for a two panel display, substantially as shown and described.

DESCRIPTION

FIG. 1 is a left side perspective view of a two panel display, showing my new design and shown as it appears when closed;

FIG. 2 is a right side perspective view of FIG. 1;

FIG. 3 is a front perspective view of the two panel display in open position;

FIG. 4 is a back side perspective view of FIG. 3; and
FIG. 5 is a top view of FIG. 3.

The broken line disclosure in FIG. 3 is for illustrative purposes only and forms no part of the claimed design.
